Primary Examiner — Marie D. Fast Horse(74) *Attorney, Agent, or Firm* — Tatonetti IP(57) **CLAIM**

The ornamental design for a bulged personal voice assisted digital interface device, as shown and described.

DESCRIPTION

FIG. 1 is a perspective view of a bulged personal voice assisted digital interface device, showing my new design; FIG. 2 is a front elevation view thereof; FIG. 3 is a rear elevation view thereof; FIG. 4 is a left side elevation view thereof; FIG. 5 is a right side elevation view thereof; FIG. 6 is a top view thereof; and, FIG. 7 is a bottom view thereof.

The broken dot-dashed lines showing the time depict environmental state of use and form no part of the claimed design; while all other broken lines depict portions of the bulged personal voice assisted digital interface device that form no part of the claimed design.
